UNITED STATES PATENT OFFICE.

GARFIELD A. WOOD, OF DETROIT, MICHIGAN.

HYDRAULIC HOISTING DEVICE.

1,271,978.

Specification of Letters Patent. Patented July 9, 1918.

Application filed March 15, 1915, Serial No. 14,480. Renewed August 1, 1917, Serial No. 183,979.

To all whom it may concern:

Be it known that I, GARFIELD A. WOOD, a citizen of the United States, residing at Detroit, in the county of Wayne and State 5 of Michigan, have invented a new and useful Hydraulic Hoisting Device, of which the following is a specification.

It is common practice to tilt the bodies of motor vehicles about pivots located near 10 the rear end of the chassis in dumping coal or other material therefrom, and liquid operated hoisting pistons have been used heretofore for that purpose. The distance the end of the body must be elevated is con- 15 siderable, which, together with the heavy loads and tendency of the body to swing laterally when elevated (due to twisting of the frame of the chassis when standing on an uneven surface), as well as the generally 20 rough usage to which the devices are other- wise subject, often cause bending of the piston rods. The present invention contem- 25 plates the use of a hollow piston rod instead, of the ordinary solid rod, whereby much greater capacity for resisting bending 30 stresses is secured without increasing the weight. The invention also aims to utilize the space above the piston between the piston rod and the cylinder, as well as the in- 35 terior of the rod itself, as a reservoir for the liquid (oil, preferably); and it includes means for venting the upper end of the hollow piston rod on the hoisting stroke and for preventing the escape of liquid there- 40 from as the piston approaches the end of the down-stroke. Other features of the in- 45 vention reside in improved means for se- curing the piston to the piston rod, and for mounting a cross piece in the upper end of the piston in position to support elements (as shown, sheaves and cables) for connect- 50 ing the piston to the free end of the body, or any other load.

In the drawings, Figure 1 is a fragmen- 55 tary side view of a motor truck showing one embodiment of my invention, the forward end of the hoisting cables and their anchorage being omitted. Fig. 2 is a front elevation corresponding to Fig. 1, parts being omitted. Fig. 3 is a vertical longitudinal section through the hoisting cylinder. Fig. 4 is a section of the upper end of the piston at right angles to Fig. 3. Fig. 5 is a 55 sectional view showing a modified form of venting means for the piston rod. Fig. 6

is a fragmentary section on the line 6—6 of Fig. 1.

Similar reference characters refer to like parts throughout the several views.

Upon the rear end of each of the side 60 frames 1 of the truck is rigidly secured a bracket 2 bearing a pivot 3 about which the body 4 may be swung vertically for dumping purposes; and the body may be provided at its lower side with the longitudinal frame 65 pieces 5 so arranged as to rest, when in lowered position, either on the side frames 1 or in special chairs carried thereby (not shown). This general construction is well 70 known.

The side frames may be cut away at a point forward of the front end of the body as indicated at 6, and may there support the cross bars 8 (preferably angle-irons 75 having their horizontal flanges facing each other) upon which rests the flanged base 9 of a hoisting cylinder 10, the latter of which may be inclined rearwardly and secured to the base by a screw joint 11 (Fig. 3). At its upper end, the cylinder may pass through 80 an expansion chamber or tank 12 which is in free communication with the interior of the cylinder by means of the lower passage 13, and the upper passage 14. The filling 85 opening of the chamber is closed by a plug 15, and in the bottom is a gland 16 whereby a discharge pipe 17 may be clamped in place. Various means may be employed for securing the expansion chamber in position; as 90 shown, the upper end of the cylinder is reduced to form a seat 18 (preferably conical) against which the chamber is clamped by a flange 19 of a stuffing box 20 threaded into the interior of the upper end of the 95 cylinder at 21.

Mounted to slide in the box 20 is a hollow piston rod 22, the upper end of which is closed by a diaphragm 24; the lower end of the rod is preferably threaded on the annular shoulder 25 of a piston 26, which may be provided with the usual piston rings 28. The piston may have projecting from its lower end the stud 29 that contacts with the base and carries the weight when in lowered position. Free passage of liquid 100 between the inside of the rod and the annular space around it is secured by the holes 30 just above the piston, whereby the interior of the rod may also be utilized for storage purposes. And, in order to admit 110

air to the upper end of the rod to allow the liquid to pass out into the cylinder as the piston rises, there is provided a tube 31, the upper end of which is just below the dia-
 phragm, the lower end opening through the piston wall somewhat below the stuffing box 20 when the piston is in lowermost position. This arrangement of the parts is partic-
 10 ularly important in that it prevents any es-
 cape of oil as the piston rod sinks. The construction is also extremely cheap and re-
 liable. The joint between the piston rod and the box 20 may be sealed by the thread-
 ed packing ring 33 and the packing 34.
 15 It will be understood that the liquid by which the piston is elevated is normally stored in the annular space above the piston, in the hollow rod and in the expansion chamber. Obviously, it may be pumped
 20 from the storage space to the pressure space beneath the piston by various devices, but it is preferred to use a gear pump 36 bolted or otherwise secured at 38 to the base 9 and driven from the propeller shaft 39 of the
 25 vehicle by means of clutch mechanism 40 controlled by the levers 41, link 42 and lever 43. The valve shaft of the pump is shown at 44 and may be operated by the lever 45, link 46 and lever 47. The reservoir dis-
 30 charge pipe 17 previously referred to leads to the intake fitting 48 of the pump, and liquid is discharged into the space beneath the piston through the passage 49. As in-
 35 dicated in Fig. 6, the interior of the pump casing may be provided with the passage 50 that leads from the suction side to the pres-
 40 sure side of the gears 51-52 (through the latter of which the propeller shaft passes) and is connected to the pipe 17 by the pas-
 45 sage 53. It is also connected to the passage 49 by the three-way valve 54 rigid with the valve shaft 44.
 50 The use of the hollow piston allows a cross-bar 60 to be firmly supported by being passed through a hole in the upper end of the rod. Each end of the cross-bar is grooved at 61 to receive a shackle 62, portions of which extend downwardly from either side of the bar to support a pivot pin
 55 63, upon the latter of which a second shackle 64 bearing the shaft 65 and pulley 66 is adapted to swing. Secured to the base 9 or other fixed part of the hoist is a shackle 68 (Fig. 2) to which an equalizing bar 69 is pivoted at 70; and attached to the ends of the latter are the cables 71 that pass over the pulleys 66 and are secured to the brackets 72, rigid with the body. The ends 73 of the shackle 62 are bent to conform to the
 60 curvature of the pulley whereby the cable is retained in position thereon.

In Fig. 5 a modified form of venting device is shown which consists in a valve 75 arranged to be forced into engagement with a seat formed in the diaphragm 24 by a

float 76. The valve is retained in operative relation to the seat as the liquid sinks by a stem 78 and cross-piece 79.

Operation.

The parts are normally in the position shown, the upper level of the oil (or other liquid) being considerably below the upper wall of the chamber 12 in order to allow for expansion. As the liquid is subjected to violent churning or agitation by the pump it soon heats and tends to become frothy and of greater volume, and the lighter or more frothy parts, if allowed to be drawn back to the pump, would greatly impair its op-
 70 eration; the chamber 12 is, therefore, as shown, made of such size as to allow for the expansion of the liquid and the accumu-
 75 lation of the light frothy portion in the space above the current of liquid that passes from the interior of the cylinder to the pipe 17—in other words, above the passage 13. The drawing off of the liquid through this chamber eliminates any necessity for additional piping and connections, which would be difficult to apply to the thin cylinder.
 80 When it is desired to hoist the load, the clutch lever and pump valve are manipulated in the proper manner and oil is drawn from the reservoir and forced beneath the piston. As soon as the piston has been ele-
 85 vated a distance sufficient to cause the lower end of the tube 31 to clear the packing ring 33, air rushes in through the tube and the contents of the rod thereafter runs out into the annular space surrounding it and is delivered to the expansion tank as the piston rises. This action maintains a liquid seal over the entrance to the pipe 17 and pre-
 90 vents air from being sucked into the pump. The piston may be lowered by turning the pump valve in position to allow the oil to escape back through the passage 49 and pipe 17 into the tank cylinder and piston rod without passing through the gears 51-52, the air escaping through the tube 31. However, before the liquid can possibly overtop the tube, the lower end of the latter will have passed into the packing ring 33, thus preventing any of the liquid from es-
 95 caping. Since the upper end of the tube is located just beneath the diaphragm, the liquid may rise until substantially the entire capacity of the piston rod is utilized for storage purposes. When it is desired to lower the body, the valve 54 is turned into the position shown (Fig. 6) which allows the liquid to by-pass the pump gears.

It will be observed that the upward move-
 100 ment of the piston is automatically limited by the port 13; in other words, as soon as the piston rises above the port the liquid circulates in an endless loop, one limb of which includes the pipe 17 and the pump while the other includes the passage 49 and

70

that portion of the cylinder below the piston. The expansion chamber is therefore at the highest point in the loop and is in communication with both branches thereof at substantially the highest point, thus preventing the air and more frothy and compressible elements of the oil from getting into or continuing in circulation, which would impair the efficiency of the hoist. 5 By providing the port 13, the necessity of throwing out the clutch or shutting down the engine as the piston approaches the upper end of the cylinder is obviated. It will also be seen that when the piston is at 10 its upper limit of movement both branches of the loop are in communication at substantially their highest point (through the passages 14 and 30 and the pipe 31) with the atmosphere. Putting it another way, the 15 space below the piston is then in communication with the atmosphere through the passages 13 and 14 and the interior of the rod. Besides freeing the liquid of froth, as stated above, the piston is therefore prevented 20 from becoming locked in its uppermost position.

It is clear that many changes may be made in the details of construction without departing from the spirit of my invention.

30 I do not, therefore, wish to be limited otherwise than as indicated by the subjoined claims.

I claim:—

1. Hoisting mechanism comprising a cylinder having an upper and a lower end, a piston slideable in the cylinder, a hollow piston rod connected to the piston and having its upper end passing out through the upper end of the cylinder, said piston rod 35 being in communication near its lower end with the interior of the cylinder above the piston to form storage space for liquid, a closure extending across and fixed to the piston rod at a point near its upper end, 40 the interior of the piston rod being in communication with the atmosphere at a level somewhat below the closure, and means for transferring the liquid from the storage space to the space between the lower end 45 of the cylinder and the piston whereby the piston and piston rod are caused to rise. 50

2. Hoisting mechanism comprising a cylinder having an upper and a lower end, a piston slideable in the cylinder, a hollow piston rod connected to the piston and having its upper end passing out through the upper end of the cylinder, said piston rod 55 being in communication near its lower end with the interior of the cylinder above the piston to form storage space for liquid, an imperforate closure, fixed to the piston rod, for the upper end of the latter, means for transferring the liquid from the storage space to the space between the lower end 60 of the cylinder and the piston whereby the

piston and piston rod are caused to rise, and means for admitting air to the interior of the cylinder as the piston rod rises and for preventing the escape of oil therefrom as the piston approaches the limit of its 70 down-stroke.

3. Hoisting mechanism comprising a cylinder arranged with one end above the other, a piston and piston rod slideable therein, said piston rod being hollow whereby it constitutes storage space for liquid, means for transferring the stored liquid from the interior of the piston rod to the space between the lower end of the cylinder and the piston to cause the piston and the piston rod 75 to be elevated, means for transferring the liquid back into the piston rod from the space beneath the piston, a closure for the upper end of the piston rod, means for admitting air to the interior of the piston rod 80 at a point below the closure as the piston rod rises and for preventing the escape of oil therefrom as the piston approaches the limit of its down-stroke, there being an unobstructed passage through the hollow piston rod from the lower portion thereof to 85 the closure to allow the liquid to freely rise and fall. 90

4. Hoisting mechanism comprising a cylinder, a piston slideable therein, a hollow piston rod connected to the piston and spaced from the cylinder, a closure for one end of the cylinder, said piston rod passing through the closure, means for closing the end of the piston rod remote from the piston, the interior of the piston rod being in communication with the space between the piston rod and the cylinder to form a storage space for liquid, means for transferring the liquid from the storage space to the opposite side of the piston to cause the latter to slide in one direction, and means for venting the closed end of the piston rod, said means comprising an air conduit, one end of which is located within the piston rod 100 and in proximity to the closure therefor, the other end opening laterally through the wall of the piston rod at a point more removed from the closure whereby air is admitted to the piston rod as the latter is 105 forced through the cylinder. 110

5. Hoisting mechanism comprising a cylinder having one end arranged above the other, the lower end being closed and the upper end being reduced to form a shoulder, 120 a storage tank for liquid carried by and surrounding the cylinder, means for clamping the tank rigidly against the shoulder to prevent leakage, a piston and piston rod slideable in the cylinder, and means for 125 transferring liquid from the storage tank to the space between the lower end of the cylinder and the piston for causing the latter and the piston rod to be elevated.

6. Hoisting mechanism comprising a cyl- 130

- inder having one end arranged above the other, the lower end being closed, a piston and piston rod slidable within the cylinder, said rod being of lesser diameter than the 5 interior of the cylinder whereby an annular storage space for liquid is formed, a storage tank for liquid carried by the cylinder, said tank being in communication with the annular storage space, at two different levels, 10 and means for transferring liquid from the storage tank to the space between the lower end of the cylinder and the piston for causing the latter and the piston rod to be elevated.
- 15 7. A cylinder, a member reciprocable therein, said member including a piston and a hollow piston rod connected to the piston and spaced from the cylinder, a closure for one end of the cylinder, said piston rod 20 passing through the closure, means for closing the end of the piston rod remote from the piston, said hollow piston rod forming a storage reservoir for liquid, said reciprocable member including a passage through 25 which the stored liquid may escape as the reciprocable member moves in one direction, means for venting the closed end of the piston rod, said means comprising an air conduit, one end of which is located within 30 the piston rod and in proximity to the closure therefor, the other end opening laterally through the wall of the piston rod at a point more removed from the closure whereby air is admitted to the piston rod 35 as the latter moves through the cylinder in the direction stated, and whereby liquid is prevented from escaping from the piston rod as it approaches the end of its movement in the opposite direction.
- 40 8. A cylinder, a member reciprocable therein, said member including a piston and a hollow piston rod connected to the piston and spaced from the cylinder, said cylinder including a closure for one of its ends, said 45 piston rod passing through the closure and forming a storage reservoir for liquid, said reciprocable member including a passage through which the stored liquid may escape as the reciprocable member moves in one 50 direction, means for excluding air from the piston rod during the early portion of the movement in the direction stated, and means for admitting air to the interior of the piston rod when it has moved a predetermined 55 distance in the same direction.
9. A cylinder, a member reciprocable therein, said member including a piston and a hollow piston rod connected to the piston and spaced from the cylinder, said cylinder 60 including a closure for one of its ends, said piston rod passing through the closure and forming a storage reservoir for liquid, said reciprocable member including a passage through which the stored liquid may escape 65 as the reciprocable member moves in one

direction, a closure for the end of the piston rod remote from the piston, said piston rod having a passage through its wall at a point near the closure, the whole arrangement being such that air is excluded from the interior of the piston rod during the early portion of its movement in the direction stated and is afterward admitted thereto through the last mentioned passage.

10. A cylinder, a member reciprocable 75 therein, said member including a piston and a hollow piston rod connected to the piston and spaced from the cylinder, said cylinder including a closure for one of its ends, said piston rod passing through the closure and forming a storage reservoir for liquid, said reciprocable member including a passage through which the stored liquid may escape as the reciprocable member moves in one direction, a closure for the end of the piston rod remote from the piston, said piston rod having a passage through its wall at a point near the closure, the whole arrangement being such that the entrance to the last mentioned passage is inclosed by the cylinder 80 to exclude air from the interior of the piston rod during the early portion of the movement of the latter in the direction stated, and is afterward uncovered to allow admission 85 of air thereto.

11. Hoisting mechanism comprising a cylinder having an upper end and a lower end, a closure for the lower end of the cylinder, a closure for the upper end of the cylinder, a piston and piston rod slidable in the cylinder, said piston rod passing through the last named closure, means for forming an expansion chamber at the upper end of the cylinder, said chamber being in communication with the upper end portion of the cylinder at two different levels, and means for transferring liquid from the expansion chamber to the lower end portion of the cylinder to raise the piston and piston rod.

12. Hoisting mechanism comprising a cylinder having an upper end and a lower end, an annular closure for the upper end of the cylinder, means for forming an expansion chamber exterior to the cylinder at the upper end portion of the latter, said expansion chamber being in communication with the interior of the cylinder through a passage in the wall of the cylinder at a point some distance below the upper end of said wall, means for drawing liquid from the expansion chamber and discharging it into the cylinder below the piston for elevating the latter, whereby the upward movement of the piston is automatically discontinued when the piston rises sufficiently to allow communication between the space below the latter and the expansion chamber.

13. Hoisting mechanism comprising an upright cylinder, a piston and piston rod slidable in said cylinder, sealing means for 130

the upper end of the cylinder, the piston rod passing through the sealing means, said rod being of lesser diameter than the interior of the cylinder whereby an annular storage space for liquid is formed, a storage tank for liquid carried by the upper portion of the cylinder, said tank being in communication with the upper portion of the cylinder at two different levels, said tank having an opening through which liquid may be poured for filling purposes and whereby air is allowed to escape from the storage space in the filling operation.

14. Hoisting mechanism comprising an upright cylinder, a piston and a hollow piston rod slidable in said cylinder, sealing means for the upper end of the cylinder, the piston rod passing through the sealing means, the piston rod being in communication near the piston with the space between the rod and the cylinder, means for forming an expansion chamber at the upper portion of the cylinder, and means for drawing liquid from the expansion chamber and forcing it into the space below the piston to elevate the latter.

15. Hoisting mechanism comprising a cylinder having an upper end and a lower end, a closure for the upper end of the cylinder, a piston and piston rod slidable in the cylinder, said piston rod passing through the closure, means for forming an air chamber at the upper end of the cylinder of size sufficient to allow expansion of an amount of liquid sufficient to fill a large proportion of the space inclosed by the cylinder, said air-chamber forming means being supported by the cylinder, a closure for the lower end of the cylinder, and pump means for drawing off the liquid from above the piston through the air chamber and delivering it to the space in the cylinder below the piston whereby the piston rod is projected from the upper end of the cylinder.

45 16. Hoisting mechanism comprising a cylinder having an upper end and a lower end, a closure for the upper end of the cylinder, a piston and piston rod slidable in the cylinder, said piston rod passing through the closure, means for forming an air chamber at the upper end of the cylinder of size sufficient to allow expansion of an amount of liquid sufficient to fill a large proportion of the space inclosed by the cylinder, said air chamber forming means being supported by the cylinder, pump means for drawing liquid from the upper portion of the cylinder and expelling it into the lower portion thereof below the piston, and means for automatically allowing the liquid below the piston to escape back to the pump means when the piston nears the upper end of the cylinder, whereby the pump means may run continuously.

65 17. Hoisting mechanism comprising an

upright cylinder, a closure for the lower end of said cylinder, an imperforate piston slidable in said cylinder, a hollow piston rod secured to said piston, an annular closure for the upper end of the cylinder, said piston rod projecting through the closure, a passage connecting the lower end of the rod with the space surrounding the rod above the piston, whereby the space both outside and inside of the piston rod may be used for the storage of liquid, an expansion chamber connected with the upper portion of the cylinder and supported thereby, means for drawing off the liquid at a high level through the expansion chamber and for thereafter forcing it into the lower end of the cylinder below the piston to raise the latter and the piston rod, and the parts being so constructed and arranged that the movement of the piston is automatically limited as it approaches the upper end of the cylinder.

18. Hoisting mechanism comprising an upright cylinder having a lower end, an imperforate piston slidable in said cylinder, a hollow piston rod secured to said piston, an annular closure for the upper end of the cylinder, said piston rod projecting through the closure, a passage connecting the lower end of the rod with the space surrounding the rod above the piston, whereby the space both outside and inside of the piston rod may be used for the storage of liquid, means for drawing off the liquid at a high level and for thereafter forcing it into the lower end of the cylinder below the piston to raise the latter and the piston rod, the interior of said piston rod being in free and unobstructed communication with the atmosphere for at least a portion of its stroke, and means for automatically limiting the movement of the piston as it approaches the upper end of the cylinder.

19. Hoisting mechanism comprising a cylinder having an upper end and a lower end, a closure for the upper end of the cylinder, a piston and piston rod slidable in the cylinder, said piston rod passing through the closure, means for forming an air chamber at the upper end of the cylinder of such shape that it conforms to and surrounds the upper end portion of the cylinder, said chamber being of size sufficient to allow expansion of an amount of liquid sufficient to fill a large proportion of the space inclosed by the cylinder, said air chamber forming means being supported by the cylinder, and pump means for drawing off the liquid from above the piston through the air chamber and delivering it to the space in the cylinder below the piston whereby the piston rod is projected from the upper end of the cylinder.

20. Hoisting mechanism having an upright cylinder, a piston and piston rod slid-

130

able in the cylinder, sealing means for the upper end of the cylinder, the piston rod passing through the sealing means, said rod being of lesser diameter than the cylinder 5 whereby an annular storage space for liquid is formed, an expansion tank for liquid carried by the upper portion of the cylinder and in communication with the interior thereof, and means for drawing off the liquid in the upper end of the cylinder and expelling it below the piston to elevate the latter, whereby frothy liquid is retained in the expansion chamber and excluded from the liquid drawing and expelling means.

10 15 21. Hoisting mechanism including an upright cylinder, a piston and a piston rod slidable therein, means, including a pump, connecting the upper portion of the cylinder with the space below the piston, said cylinder and connecting means forming an endless loop system, exclusive of the piston, through which liquid may be circulated, said loop system also including an expansion space of considerable size, independent 20 25 of the piston rod, in communication with both branches thereof at substantially the highest point in the latter when the piston is at the upper limit of its movement.

22. Hoisting mechanism including an upright cylinder, having an annular upper end, a hollow piston rod slidable through said end and forming therewith a tight joint, an imperforate piston fixed to the lower end of the rod, means, including a pump, connecting the upper end portion of the cylinder with the space below the piston, said cylinder and connecting means forming an endless loop system through which liquid may be circulated continuously when the 30 35 piston reaches a predetermined elevation, the piston rod and piston constituting two members, there being an opening through one of the members whereby communication is established between the lower end portion 40 45 of the interior of the rod and the space between the rod and the cylinder, the parts being so constructed and arranged that both branches of the loop are in communication at substantially the highest point in said 50 branches with the interior of the piston rod through said opening when the piston reaches the upper limit of its movement.

23. Hoisting mechanism comprising a cylinder having one end arranged above the other, a piston and piston rod slidable in the cylinder, an expansion tank surrounding the cylinder near the upper end of the latter, means for clamping the tank in sealed relation with the cylinder to form a fluid 55 60 tight joint therewith, there being a passage through the wall of the cylinder through which liquid may escape from the cylinder directly into the tank when the piston rises sufficiently to uncover said passage, and 65 means for drawing liquid from the tank and

expelling it into the cylinder below the piston to elevate the latter at will.

24. Hoisting mechanism including a cylinder having an upper end and a lower end, a hollow piston rod slidable through the upper end and in sealed engagement therewith, an imperforate piston secured to the rod, means for supplying liquid under pressure to the space below the piston to elevate the latter and for continuously drawing said liquid from the upper end portion of the cylinder when the piston reaches a predetermined elevation, the space below the piston being in communication with the atmosphere through the interior of the piston rod 70 75 and independently of any communication through the lower portion of said space when the piston reaches said predetermined elevation.

25. Hydraulic hoisting mechanism forming a circulatory system including a loop arranged with one end higher than the other, one branch of the loop including an upright cylinder, a piston reciprocable in the cylinder, a piston rod projecting upwardly from the piston, the other branch of the loop including a suction pipe through which liquid may freely pass either from or to the space above the piston, the loop also including a pump for drawing the liquid 85 through the suction pipe and forcing it under pressure into the cylinder below the piston to elevate the latter, automatic means for limiting the upward movement of the piston rod, the system further including an 90 95 expansion space located for the most part above the upper limit of movement of the piston and exterior of the cylinder through which the liquid is drawn off to the suction pipe, said space being large enough to allow for the expansion of an amount of liquid sufficient to fill a large proportion of the entire system and to separate the froth from said liquid under rapid and continuous circulation at high pressure. 100 105 110

26. In combination, an upright cylinder, a piston slidable therein, a hollow piston rod connected to the piston and passing through the upper end of the cylinder, the interior of the piston rod being in communication with the space surrounding said rod above the piston, means for drawing liquid from the upper end portion of the cylinder and forcing it under pressure into the space below the piston to elevate the latter, automatic means for the piston as it approaches the upper end of the cylinder whereby surplus liquid is allowed to escape from the space below the piston, said automatic means being so constructed and arranged that the 115 space below the piston is in communication with the interior of the piston rod when the piston stands at the upper limit of its movement, and means for maintaining the pressure on the upper surface of the liquid in 120 125 130

the piston rod substantially equal to that of the atmosphere during at least the greater part of the stroke.

27. In combination, an upright cylinder having an annular shoulder thereon, an expansion tank surrounding the cylinder and forming a tight joint with said shoulder, an annular head for the upper end of the cylinder, a piston rod construction slidable through the head, said head being constructed and arranged to hold the tank against the shoulder.

28. In combination, an upright cylinder, a piston and a hollow piston rod slidable therein, an annular head for the upper end of the cylinder, the piston rod passing through the head in sealed relation therewith, the interior of the piston rod being in communication with the space between said piston rod and the cylinder and above the piston, means for forming a plugged passage through which liquid may be poured into the piston rod through the cylinder

when the plug is removed, the upper end of the piston rod being in communication with the atmosphere at least when the piston rod is elevated, whereby the air therein may escape during the filling operation.

29. In combination, an upright cylinder, a piston and piston rod slidable therein, a combined lower end and supporting base for the cylinder, and means, including a pump attached to the base on the side thereof opposite the cylinder, for drawing off liquid from the upper end portion of the cylinder and expelling it through the base into the space between the base and the piston to elevate the latter.

In testimony whereof I sign this specification in the presence of two subscribing witnesses.
